CLAIM

The ornamental design for an airbrush system, as shown and described.

DESCRIPTION

FIG. 1 is a perspective view of an embodiment of an airbrush system showing my new design;

FIG. 2 is another perspective view of an embodiment of an airbrush system showing my new design;

FIG. 3 is a front view of the airbrush system of FIG. 2;

FIG. 4 is a rear view of the airbrush system of FIG. 2;

FIG. 5 is a left side view of the airbrush system of FIG. 2;

FIG. 6 is a right side view of the airbrush system of FIG. 2;

FIG. 7 is a top plan view of the airbrush system of FIG. 2; and,

FIG. 8 is a bottom plan view of the airbrush system of FIG. 2.

The broken lines in the drawings illustrate portions of the airbrush system which form no part of the claimed design.
